UNITED STATES PATENT OFFICE.

RICHARD W. HUBBARD, OF ASHTABULA, OHIO.

HINGE.

1,346,029.

Specification of Letters Patent.

Patented July 6, 1920.

Application filed September 2, 1919. Serial No. 321,201.

To all whom it may concern:

Be it known that I, RICHARD W. HUBBARD, a citizen of the United States, residing at Ashtabula, in the county of Ashtabula and State of Ohio, have invented new and useful Improvements in Hinges, of which the following is a specification.

My present invention pertains to hinges, and more particularly to hinges for screen doors, window screens and the like.

The object of the invention is to provide a hinge constructed with a view to being quickly and accurately hung without the employment of skilled labor, and one that is calculated to be cheaply made and is at once light in weight and stiff and strong.

Other advantageous characteristics of the invention will be fully understood from the following description and claims when the same are read in connection with the drawings, accompanying and forming part of this specification, in which:

Figure 1 is an elevation illustrating a hinge constructed in accordance with my present invention as the same appears when applied to a door casing and door.

Fig. 2 is an elevation of the hinge unapplied, and showing the opposite side of the hinge to that shown in Fig. 1.

Fig. 3 is an enlarged horizontal section of the hinge.

Fig. 4 is a vertical section taken through one of the hinge members and showing the same properly arranged relative to its complementary base plate.

Fig. 5 is a detail perspective of one of the base plates employed in combination with the hinge members.

Similar numerals of reference designate corresponding parts in all of the views of the drawings.

As hereinbefore intimated my novel hinge is designed more especially for use in connection with screen doors, and in Fig. 1, 1 indicates a door casing, and 2 the frame of a door. It is to be understood, however, that my novel hinge is capable of use in any connection to which it is applicable.

As will be readily understood by comparison of the several figures of the drawings, my novel hinge comprises base plates 3, swinging members 4, and a pintle 5. When desired, the pintle may be surrounded by a coiled spring 6, as shown in Fig. 1, but the

said spring 6 and any appurtenance, such as 55 a tubular cover inclosing the same, are not of the essence of my invention, and may therefore be omitted when desired, without affecting my invention. With the exception of the pintle 5, all of the elements comprised 60 in my novel hinge may be and preferably are made of sheet-metal.

The base plates 3 are identical in construction, and therefore a detailed description of the one shown in Fig. 5 and Fig. 4 65 will suffice to impart a definite understanding of both. The plate referred to is provided with a longitudinal-central channel portion 7 having barbs 8 which are preferably, though not necessarily, struck therefrom, and also having by preference a screw-hole 9, and flanges 10 extending from said channel portion and arranged in parallel relation to the back of said channel portion. From this it follows that when 75 the back of the channel portion is secured against the face of a door casing or a door, as the case may be, the flanges 10 will be separated by intervening spaces from the face of the door casing or door. It will also 80 be noted by comparison of Figs. 4 and 5, that the lower end of the channel portion of the plate is provided with an outwardly extending ledge 11, for an important purpose hereinafter set forth.

Either one of the members 4 may be the swinging member of the hinge. The said members respectively comprise a body portion 12, arms 13 disposed at right angles to said body portion, and side flanges 14 on 90 the body portion and extending in opposite directions therefrom, with reference to the arms 13. The arms 13 are connected in hinged manner with the pintle 5, and the body 12 of each member 4 is designed to 95 bear at its lower end on the ledge 11 of its complementary base plate 3, while the flanges 14 are designed to embrace the side edges or flanges 10 of the base plate, all as clearly shown in Fig. 3.

The practical advantages of my novel hinge will be best understood from a description of the manner of putting the hinge into use, and in this connection I would say that I prefer to pack and ship 105 the hinges with the parts relatively arranged or assembled as shown, Fig. 3. I also prefer to use the base plates after the

manner of templets, that is to say, I take the hinge as shown in Fig. 3, and place and hold it with one hand in the position it is to occupy, and then with a hammer held in the other hand I tap the hinge so as to drive the barbs slightly into the wood and form marking holes. I then slip the base plates out of the hinge members, and first position the barbs of the plates in the marking holes previously made, and then drive the barbs of the base plates home—*i. e.*, until the backs of the channel portions 7 bring up against the faces of the door casing and door. I then drive a screw through the aperture 9 of each base plate, and it will be manifest that the base plates so secured cannot be otherwise than in the proper positions. It will also be appreciated in this connection that the barbs 8 are calculated to hold the base plates securely and are equal to screws in withstanding weight and strain placed on the hinge. After the base plates have been correctly placed and secured on a door casing and door, the hinge is completed and connection of the door with the casing is effected by slipping the connected members 4 over the base plate so that the member flanges 14 embrace the flanges 10 of the base plates, and so that the bodies of the members bear at their lower ends on the ledges 11 of the base plates. Manifestly this is a very simple and easy operation, and from the same it follows that when it is desired to disconnect the door from the casing the same can be readily accomplished by merely lifting the connected members 4 off of the base plate. Then the door and the connected members 4 can be stored away, with the result that only the base plate complementary to the door casing is left exposed to the inclement weather of winter. In this connection I would say that when deemed expedient the base plates and screws used in connection therewith may be treated in any manner that will prevent rusting thereof. I would also have it understood that the hinge members snugly receive and tightly fit the base plates, and hence there is no liability of a light door moving downwardly relative to the door casing when the ledges 11 are arranged at the lower ends of the base plates, as illustrated in the drawings. I would have it distinctly understood, however, in this connection, that when desired the ledges 11 of the base plates may be arranged at the upper ends thereof instead of at the lower ends, without affecting my invention.

It will be gathered from the foregoing that my novel hinge obviates the difficulties experienced in removing screen doors for the winter and in rehanging screen doors, and that the hinge may be depended on to prevent sagging of the door. It will also

be appreciated that the hinge is light in weight, and at the same time is stiff and strong. It will further be noted that the hinge is susceptible of being quickly and cheaply made, and that the broad bearings of the arms of the hinge members against the ledges 11 contribute materially to the strength and durability of the hinge.

Because of the fact that my novel hinge may be employed in connection with the well-known house door and the further fact that when so used it will be necessary during the handling and detaching operation to hold the hinge about half open or a little more, I place small registering holes through both halves of the hinge near the upper end thereof at the point indicated by the numeral 20 and as near the edge of said halves as possible to clear the spring 6. Such holes when placed in the hinge halves, will simply necessitate the dropping of a pin 85 therein and thus hold the halves open during detaching and hanging of the door. This, however, is a mere matter of discretion on the part of those practising the invention.

Having described my invention, what I claim and desire to secure by Letters-Patent, is:

1. In a hinge, the combination of a base plate having a longitudinal central channel extending throughout the length of said plate whereby a raised portion is produced, barbs struck from said channel, a screw hole in said channel, between the barbs, flanges extending from said channel portion and arranged in parallel relation thereto, arms formed integral on the ends of the raised portions of the base plates, and members comprising a body portion, a ledge formed on the lower ends of the channel, arms formed integral on the ends of the body portions and disposed at right angles thereto, side flanges formed in the body portions, and extending throughout the lengths of the body portions and in opposite directions with respect to the arms of the body portions, a pintle for connecting the arms in hinged manner, whereby the body members will rest on the ledge of the channel of the base plates and the flanges of the body members will embrace the parallel flanges of the channel portion.

2. In a hinge the combination of a base plate having securing means arranged therein, whereby it may be fastened to a door casing and frame, side flanges that extend throughout the length of the plate whereby a channel is formed in the longitudinal center of the plate, outwardly directed walls formed integral on the ends of the channel, and a body member having arms at its ends, an aperture in said ends whereby they may be hinged together, flanges arranged on and extending throughout the

lengths of the body member and having a groove formed on each side of the body member in which the flanges of the base plate rest; said body member being so constructed and arranged so as to abut against the end walls of the base plate.

In testimony whereof I have hereunto set

my hand in presence of two subscribing witnesses.

RICHARD W. HUBBARD.
